METHOD OF MAKING STAPLE BLOCKS

Filed April 30, 1930

FIG. 2.

FIG. 3.

INVENTOR
PAUL F. TITCHENER.
Eric Schlinger,
ATTORNEY

UNITED STATES PATENT OFFICE

PAUL F. TITCHENER, OF BINGHAMTON, NEW YORK, ASSIGNOR TO OSCAR D. GIBBS AND ERIC ISCHINGER, BOTH OF ROCHESTER, NEW YORK

METHOD OF MAKING STAPLE BLOCKS

Application filed April 30, 1930. Serial No. 448,715.

This invention relates to staples adapted to be used in stapling machines and has for one of its objects to provide a new and improved method and means whereby a plurality of such staples may be fastened together to facilitate their insertion into the magazine of the stapling machine.

Another object of the invention is to include in the fastening means a reinforcing member.

Another object of this invention is to apply the reinforcing member of the fastening means to the staples so that it provides a smooth surface extending the full length of the row of staples which are held together by the fastening means.

Another object of this invention is to provide a method by which the reinforcing member of the fastening means is automatically attached to the staples.

These and other objects of this invention will be apparent from the drawing, the specification and the appended claims forming a part thereof.

In the accompanying drawing:

Figure 1 is a perspective view of a row or block of staples fastened together with the reinforced fastening means.

Figure 2 is a longitudinal sectional view of the block of staples illustrated in Figure 1, the section being taken on the line 2x—2x of Figure 1.

Figure 3 is a perspective view of a block of staples in process of having the reinforcing member attached thereto.

Figure 4 is a detail perspective view of a portion of one of the staple blocks in which the reinforcing member is located on the inside of the staples instead of the outside thereof.

In the several figures of the drawing like reference numerals indicate like parts.

The method and means for fastening a plurality of staples into blocks forming the subject matter of my present invention is especially adapted for use with large and heavy staples although smaller and lighter staples may be held together by this same method and means. The larger and heavier staples are particularly intended for use in stapling machines for stapling heads into

barrels and kegs and such staples must be heavy to be strong enough so that they can be forced thru the thin steel hoop of the barrel or keg into the edge or perimeter of the head.

The staples are automatically made in suitable machines at a rapid rate of speed and are ejected so that they either line up themselves on a suitable guide member (not shown) or are readily lined up thereon by the attendant of the staple making machine. The guide member comprises a rod or bar of suitable cross section and dimension which enables the staples to straddle it so that a plurality of them can be supported and lined up thereon with relation to each other. The staples, as illustrated in the figures are preferably grouped in a block of twenty-five, fifty or one hundred and each has a straight back 2 and the shanks or sides 3 and 4 which project at right angles from their back 2 parallel to each other. The free ends of the shanks 3 and 4 have the nail or pyramid shaped points 3A and 4A provided thereon so that the staples, when driven from the stapling machine, will follow a straight course and will not deflect to either one side or the other thereof.

After a number of staples are made and temporarily held together side by side in a continuous row, glue or other suitable binding material is applied to the outside of the staples. This may be done by either painting the outside of the staples with the binding material or dipping the staples into the fluid binding material so that the desired amount of binding material will adhere to the proper surface and is coated thereby. In practice both sides and the back of the staples or either the one or the other, or just one side and the back may thus be coated with the binding material which preferably consists of a quick drying glue of good adhesive quality.

The row of staples thus coated is then placed on the reinforcing material 5 as illustrated in Figure 3; that is, with the back of the staples resting on the reinforcing material. The binding material, which has been applied to the back of the staples, flows down

the sides thereof because of its still liquid or semi-liquid state, and thus binds the reinforcing material to the back of the staples and fills the spaces between the staples and the reinforcing material. The reinforcing material 5 is preferably a sheet of paper of a grade and quality of that of news paper stock or similar thereto. Of course a higher grade of paper and correspondingly stronger texture may be used instead but the cheaper grade has been found satisfactory for the purpose. Other reinforcing material such as woven fabric of one kind or another may of course also be substituted for the paper if it is found desirable to increase the strength of the reinforcing material.

The reinforcing material 5 is supported flat so that when the backs of the staples are placed on it, they are held in line with each other and form a block having a straight continuous back and correspondingly straight and continuous sides. The sides or shanks 3 and 4 of the staples are held together by the adhesive properties of the binding material, the outside of which has been coated and a certain amount is located between the successive sides or shanks of the staples. Unless the binding material is however reinforced with a reinforcing material having a tensile strength greater than that of the binding material it has been found in practice that the heavier staples will easily break away from each other. To prevent the sides or shanks of the staples from breaking away from each other the reinforcing material 5 is therefore applied to the back of the staple blocks. Furthermore a cheaper binding material may be used with the reinforcing material and still have the staples bound together with a far greater binding force than is developed by the best of binding materials.

While I have illustrated the staples as having the reinforcing material applied to the back of the staples it is readily seen that the reinforcing material may be applied to either one side or the other by simply placing the block of staples with one side on the reinforcing material instead of with the back as illustrated in Figure 3. The reinforcing material is preferably a large sheet and many blocks of staples may be placed on it side by side and end to end and allowed to rest thereon until the binding material is thoroughly dry. The reinforcing material is then severed between the blocks of staples to separate them after which the reinforcing material may be trimmed as illustrated in Figure 1 so that it will not overhang the sides of the block of staples and permit their ready insertion into the magazine of the stapling machine.

In Figure 3 I have illustrated the reinforcing material applied to the inside of the back of the staple block. In this case the reinforcing material is made up in a strip 6 which

is placed into the block and held against the inside of the back of the staples in any suitable manner in which the staples are at the same time held in line with each other in a straight continuous row. The staples may also be coated and held together by means of the binding material alone and then afterwards have the reinforcing material applied separately to either the outside or inside of the block thus formed.

75

Paper stock is used for the reinforcing material because it is a fibrous material of sufficient tensile strength and provides a reinforcing means which can be readily severed in the stapling machine to permit individual staples to be ejected therefrom.

80

I claim:

1. The method of fastening a plurality of staples into a block which consists in coating a portion of a series of the staples with a liquid binding material placing the coated portion of the series of staples onto a sheet material while the liquid binding material is still in the liquid state in order to hold the binding material between the sides of the individual staples during the drying period.

85

2. The method of fastening a plurality of staples into a block which consists in coating large sections of a series of the staples with a liquid binding material and then placing the series of staples with their large coated section on a fibrous binding material to allow the liquid binding material to collect between the sides of the individual staples and hold this liquid binding material between the sides of the individual staples while drying.

90

3. The method of fastening a plurality of staples into a block which consists in coating a portion of the outside of the staples with a liquid binding material and then placing the coated portion of the staples onto a thin fibrous sheet material and permit it to dry thereon and hold the binding material between the sides of the individual staples and the sheet material while drying.

100

4. The method of fastening a plurality of staples into a block which consists in first coating a portion of a series of the staples with adhesive binding material and then supporting the coated portions of the staples in a continuous row on a fibrous sheet material to have the binding material collect and dry between the staples and on the fibrous sheet material to bind consecutive staples to each other and the fibrous reinforcing sheet material.

105

In testimony whereof I affix my signature.

PAUL F. TITCHENER.
